United States Patent Office.

ALFRED WEED, OF BOSTON, MASSACHUSETTS.

Letters Patent No. 78,499, dated June 2, 1868.

IMPROVEMENT IN SELF-BORING STOP-COCKS.

The Schedule referred to in these Letters Patent and making part of the same.

TO ALL WHOM IT MAY CONCERN:

Be it known that I, ALFRED WEED, of Boston, in the county of Suffolk, and State of Massachusetts, have invented an Improved Faucet; and I do hereby declare that the following, taken in connection with the drawings, which accompany and form part of this specification, is a description of my invention sufficient to enable those skilled in the art to practise it.

The invention relates particularly to the construction of that class of faucets which are provided with means for boring or tapping casks.

The drawings represent a faucet embodying my invention—

A showing a reverse plan, and

B a vertical central section of the same.

a denotes the main body or barrel of the faucet, cast with a closed end, *b*, and with lateral induction-openings *c*, the end piece having fixed permanently thereto a bit, *d*, for boring into the cask, to apply the faucet.

To enable the faucet to be readily turned, to enter the bit, the head of the faucet is provided with two opposite lateral projections or spines, *e*, which are readily grasped by the hand, and serve, like the handle of a gimlet, to turn and press inwards the bit.

To bring the induction-end of the faucet to proper position within the cask, and with the induction-head as near to the cask as may be desirable, the thread *f*, by which the faucet is screwed in after the hole has been bored, is cut at a considerable distance from the entering end, as seen in the drawing, leaving a smooth surface, *o*. When the screw-thread is continued to the extreme end of the faucet, it is oftentimes difficult to insert the same, as the auger or bit which taps the hole often fails to make a clean or perfect bore, but by making the surface smooth at the end, the faucet may be pushed in by the hands, having hold of the spines, after the hole is tapped, until the screw-thread meets the wood, when the faucet may be readily screwed in, still using the spines to turn the faucet by.

The head, *g*, of the faucet is made globular or bulbous, and the orifice *h*, which is at the under side of the same, is provided with a valve, *i*, this valve being fixed to a vertical stem, *k*, passing through the upper part of the head, the stem being provided with a knob, *l*, for raising and lowering the valve.

The valve is made of an elastic washer, *m*, enclosed between two metal disks, *m n*, the lower washer working on a screw-thread cut on the spindle, and compressing the elastic washer against the inner disk, *n*, which abuts against a shoulder on the stem, such compression expanding the washer radially, and causing it to fit closely to the sides of the orifice.

When raised, as seen by dotted lines at *B*, it will readily be seen that an unobstructed passage is left for flow of liquid running through the faucet.

The faucet is designed particularly to be used as a molasses-faucet, and the construction and arrangement of the valve obviate the difficulties and objections pertaining to such faucets as have external gates, or as have plug-valves.

The faucet is very simple in construction, requiring no nice fitting of parts, and has the advantage of combining directly with the faucet the means of application to a cask.

I claim a faucet, provided with a screw-thread, *f*, on its barrel, for the purpose set forth, its entering-end provided with a closed boring-tool, *d*, and the blank or smooth surface, *o*, between the screw-thread and the boring-tool, in which blank surface are the inlets *c*, communicating with the passage through the faucet, and also provided with handles *e*, by which the borer is turned, the smooth surface pushed into the tap-hole, and the faucet turned as it is screwed into the tap-hole.

ALFRED WEED.
